(57) **CLAIM**

We claim the ornamental design for an inside door handle for motor vehicle, substantially as shown and described.

DESCRIPTION

FIG. 1 is a perspective view of an inside door handle for a motor vehicle showing our new design, the undisclosed portion is not part of the claimed design;

FIG. 2 is a top plan view thereof;

FIG. 3 is a side elevational view thereof;

FIG. 4 is an opposite side elevational view thereof;

FIG. 5 is an end view thereof; and,

FIG. 6 is an opposite end view thereof.

No claim is made to a bottom plan view of the handle, or to the structure shown in broken lines in the drawings.

The broken lines are included for the purpose of illustration and form no part of the claimed design.
